SHUTTLE BOX CONSTRUCTION FOR LOOMS

Benjamin W. Brouwer, Auburn, Mass., assignor to Crompton & Knowles Loom Works, Worcester, Mass., a corporation of Massachusetts

Application October 1, 1936, Serial No. 103,556

9 Claims. (Cl. 139—183)

This invention relates to improvements in shuttle box constructions for looms capable of using two types of boxes so they can be converted from weft replenishing to pick and pick and it is the general object of the invention to provide a lay with a part which can be common to both types of boxes.

In the production of a variety of fabrics it frequently happens that one kind of cloth can most efficiently be woven on a weft replenishing loom while another type requires more shuttles than can conveniently be used on the automatic loom. In order that these fabrics may be woven without requiring two entirely different looms it has been proposed to provide a loom which is convertible, a weft replenishing magazine being set in operating position at one time and being removed to an idle position to provide room for a set of shifting shuttle boxes when pick and pick fabrics are to be made.

When shifting shuttle boxes are used there is generally provided a pair of guide plates having grooves to receive tongues at the ends of the gang of boxes. These tongues and grooves serve to align the box backs with the reed to insure proper flight of the shuttle. It is equally necessary that the back of the plain or single box used with the magazine also be aligned with the reed. It is an important object of my present invention to secure permanently to a part of the lay a guide to serve the usual function with shifting shuttle boxes, but capable of cooperating with a positioning tongue on the single box. In this way the relation between the reed, the guide tongue on either type of box, the groove of the guide plate and the back of either type of box is the same in both instances.

In order to insure proper flight of the shuttle the boxes are sometimes tilted slightly, the pitch being down so that the shuttle may always tend to run close to the shuttle race. The picker stick is located close to the guide for the outer tongue of the shifting boxes and the vibration due to shuttle boxing is absorbed by a bunter which lies between the guide plate and the lay end. As heretofore constructed the bunter has been forced against a part which is integral with the lay, hence the plate could be given a slightly oblique position which would not be disturbed by shuttle boxing. In the present instance, however, the necessity for being able to use a single box makes it impossible to use the previous construction and it is a further object of my invention to provide a block between the lay end and the box guide separate from both of these

parts to be used with the gang of boxes and held to the lay by a tongue and groove connection. The block supports the guide plate so that the latter can be adjusted angularly to give the proper pitch to the shuttle.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is an end elevation of the upper forward part of a loom having my invention applied thereto with the lay in section, the magazine being shown in transferring position,

Fig. 2 is a front elevation on an enlarged scale looking in the direction of arrow 2, Fig. 1,

Fig. 3 is a detached perspective view of the single box forming elements,

Fig. 4 is a plan view of the structure shown in Fig. 2,

Fig. 5 is a front elevation taken in the direction of arrow 5, Fig. 1, but showing the loom equipped with shifting shuttle boxes and the magazine swung to an inoperative position,

Fig. 6 is a detached perspective view of certain parts used when shifting shuttle boxes are employed at the magazine end of the loom,

Fig. 7 shows an assembly position of the shifting boxes taken along line 7—7 of Fig. 5 and showing the boxes as they are being either removed from the loom or inserted to permit pick and pick weaving,

Fig. 8 is a view similar to Fig. 7 but with the shifting boxes in a normal position,

Fig. 9 is an end elevation taken in the direction of arrow 9, Fig. 2, and

Fig. 10 is a perspective view of a block used when shifting shuttle boxes are employed at the magazine end.

Referring to the drawings, the loom frame 10 has a supporting structure 11 for a pivot 12 around which the magazine M can be swung from the full to the dotted line position of Fig. 1. When in the full line position the magazine cooperates with the single shuttle box to be described hereinafter and when the loom is to be operated pick and pick the magazine is swung to the dotted position. A support 13 may be provided to hold the magazine in its idle position.

The lay L moves back and forth in the usual way and carries a protector rod 14 with a protector finger 15 which operates as usual with the binder of the active shuttle box aligned with the shuttle race 16. An inner box guide 17 fixed

relatively to the lay has a groove 18 which serves to position both the stationary and the shifting shuttle boxes to be described.

A box lifter chain 20 is attached as at 21 to a sleeve 22 movable vertically with respect to a foot 23 on a rocker shaft 24 which supports the lay through swords one of which is indicated at 25. A box lifter rod 26 passes through the sleeve 22 and is surrounded by a spring 27 strong enough to hold the nut 28 on the rod 26 normally against the under side of the sleeve 22. A rod 29 extends through a finger 30 of the sleeve to receive the downward thrust of spring 31 to prevent overriding of the box lifter rod when the latter is raised.

The matter thus far described is of the usual construction, the method of mounting and handling the magazine being substantially the same as that set forth in co-pending application Serial No. 74,519 and the magazine if desired being of the general form shown in Patent No. 1,563,592.

In carrying my present invention into effect I provide an improved form of lay end E having rearwardly extending ears 35 to support a picker spindle 36, see Fig. 4. A horizontal elongated slot 37 is formed in the lay end opposite the spindle 36 and has outer and inner enlargements 38 and 39, respectively, for a picker 40 indicated in dot and dash lines in Fig. 4.

30 The lay end has a vertical wall 42 from the lower end of which projects forwardly a floor 43 perforated as at 44 for the box lifter rod. The wall and floor may be connected by a reinforcing end web 45 if desired and the inner or left end of 35 the lay end as viewed in Fig. 4 may be secured to the lay as at 46. The upper wall 47 of the lay end has tapped holes 48 and 49 below the slot 37 and may also have dowel holes 50 and 51. The forward face 55 of the upper wall 47 is flat and 40 vertical as indicated in Figs. 3 and 4. There is also a bolt slot 56 preferably aligned with the enlargement 38. The lay end is secured permanently to the lay and is the structure to which either the single box or the set of shifting boxes 45 is applied depending upon whether the loom operates automatically or pick and pick.

When the loom is to be operated automatically with the magazine in the full line position of Fig. 1 there is used a single shuttle box designated 50 generally at B, the principal forming part of which is the element 60 shown as the central part of Fig. 3. This element or box former has a floor 61 with an elongated slot 62 to permit the passage of depleted bobbins and there projects 55 forwardly from this floor a bunter 63 which takes part in a transferring operation of the loom. A binder guide 64 extends upwardly from the floor adjacent the inner forward end thereof.

A rear wall 65, preferably integral with the 60 floor 61, is provided with a slot 66 which aligns horizontally with the slot 37 and this slot has outer and inner enlargements 67 and 68, respectively, which align with the enlargements 38 and 39, respectively. The wall 65 has extending along 65 the upper edge thereof a narrow top 70 which serves to prevent upward displacement of the shuttle.

A depending wall 71, preferably an extension or continuation of wall 65, extends downwardly from 70 the floor to lie along the lower part of surface 55. Screws 72 extend through the lower wall 71 and are threaded into the tapped holes 48 and 49 to hold the wall 71 tightly against the surface 55, while dowels 73 secured permanently to the 75 wall 71 fit the dowel holes 50 and 51.

The left or inner end of wall 65 is provided with a tongue 75 as shown in Fig. 3 which fits into the groove 18 of the guide 17. When assembling the element the tongue is fitted into the guide groove and the dowels into their holes after 5 which the screws 72 are tightened. The front surface 76 of the wall 65 is in alignment with the front surface 77 of the guide 17, this relation being maintained by the tongue and groove connection between the wall 65 and the guide 17. 10 As a shuttle is picked from this box therefore it passes smoothly from the wall 65 to the guide.

The binder 80 has bolted thereto a strap 81 through which extends a screw 82, the head 83 of which confines the strap. The screw 82 is 15 held tightly to a binder block 84 having a bolt hole 85 to align with a bolt slot 86 in the outer wall 65 and the bolt slot 56 in the lay end. Bolt holes 87 in the outer part of the plate or floor 61 receive bolts 88 which fasten the block 84 20 down on the floor, while a bolt 89 passes through the aligned holes 85, 86 and 56 to hold the block 84 against the front face of wall 65. The binder has a tongue 90 which fits into the binder guide 64, and a pressure finger 91 may be provided to 25 engage the strap 81 and tend normally to hold the binder rearwardly in shuttle checking position.

The finger 91 is mounted loosely on a shaft 92 journaled as at 93, see Fig. 2, and has the outer end thereof supported by a bearing 94 held to 30 the bottom of the floor 61 by bolts 88 shown in Fig. 9. A spring arm 96 secured to the shaft 92 operates to exert a rearward yielding pressure on the finger 91, and the shaft 92 is controlled by an arm 98 to oscillate the shaft. The parts 35 associated with the shaft 92 may be substantially the same as those shown in the prior Santon Patent No. 2,045,967 and copending Darwin application Serial No. 59,253.

In that part of my invention thus far described 40 the box element 60 and binder 80 constitute a single box to be located on the lay under the magazine when the latter is in transferring position with the element 60 bolted to the wall 47 and positioned by the dowels and the tongue and 45 groove connection already described. During a weft replenishing operation the outgoing bobbin passes through slot 62 in well-known manner and the bunter 63 actuates the transerrer arm not shown but forming part of magazine M. 50 So long as the loom is to be operated automatically the single box remains attached to the lay, the picker passing along the aligned slots 37 and 66 to drive the shuttle out of the box. When 55 it is desired to operate the loom pick and pick the single box is removed in a manner which is thought to be apparent from the drawings and previous description, after which the shifting boxes are applied as will now be described.

As shown herein I have set forth a gang G 60 of four shuttle boxes or cells 100 which are mounted on the upper end of the box lifter rod 26. These boxes are preferably cast as a single unit and have inner and outer vertical guide tongues 101 and 102 which fit, respectively, the previously described guides 17 and a specially formed guide 103. The latter comprises a plate 104 having a groove 105 to receive the tongue 102 and the lower part of the plate has a perforation 106 in alignment with the tapped hole 107, while the intermediate outwardly extending projection 108 of the plate has a bolt slot 109 in alignment with the previously described bolt slot 56. The plate 104 may have extending rearwardly 75

therefrom shuttle point engaging wings 110 between which the picker moves.

In order that the plate 104 may be spaced from the wall 47 I provide a spacer block 115 having a bolt slot 116 in alignment with similar slots 56 and 109. The block has a vertical tongue 117 on a web 118 to fit a corresponding groove 119 disposed vertically in the wall 47 of the lay end. The plate and block may be held securely to the lay end by the same bolt 89 used with the single box, the tongue 117 and groove 119 preventing angular movement of the block 115 relatively to the lay end. The bolt, however, permits a slight angular adjustment of the plate 104 relatively to the block so that the pitch of the shuttle cells 100 may be made slightly oblique with respect to the lay. The bolt 120 passing through the hole 106 and into the tapped hole 107 may hold the lower part of the plate securely to the lay end and may also if desired serve as a pivot around which the plate is moved when being angularly adjusted, the hole 109 being sufficiently large to permit this slight motion.

The block 115 is hollow as suggested in Fig. 10 to receive a picker bunter 112, and in this connection it may also be stated that binder block 84 is also hollow to receive a bunter. The width of block 84 plus the thickness of wall 65 is substantially the same as the combined thickness of plate 104 and width of block 115, hence the same bolt 89 can be used with either the single or multiple box construction.

With the guide plate 104 thus positioned the gang of boxes G can be moved by the rod 26 to vertical positions in response to the demand of the pattern being woven, and at this time the magazine will be thrown back to the dotted position of Fig. 1 so as not to interfere with the shifting shuttle boxes G when they are in their highest position and the lay is rearward. The gang of shuttle boxes is provided with a series of picker slots 125 which align with the slot 37 of the lay end whenever the corresponding cell is opposite the lay end in picking position.

Fig. 7 is an assembly view showing a gang of boxes G being either raised from the lay end when the loom is to be changed back to weft replenishing or being applied to the lay end when the loom is to be operated pick and pick. It will be seen that the rod 26 is in position to enter the sleeve 22 and passes through the slot 44 in the floor 43. When the gang of boxes is down they assume the position shown in Fig. 8, at which time the nut 28 is in position to hold the cells in proper position for alignment with the lay. Removal of the gang G and the rod 26 can thus be readily effected and the remainder of the drop box guiding and lifting mechanism will be held in position by spring 31 which will exert a downward pressure on the sleeve to hold the chain 20 taut. Under these conditions the pattern mechanism at the opposite end of the loom will ordinarily be built to cause no motion of the box chain 20 and it has been found in practice that the bobbin can ordinarily be used for the reception of outgoing bobbins and can be fitted under the lay end in front of the sleeve 22 without being interfered with by the latter.

From the foregoing it will be seen that I have provided a construction whereby a single lay end can be used and have applied thereto either a single shuttle box or a gang of shifting boxes. When the single box is used it will be seen that the inner guide 17 serves to position the rear wall 65 of the single box. Furthermore, the

block 115 is separate from the plate 104 so that the latter may be adjusted angularly with respect to the lay despite the fact that the tongue 117 fits closely into the groove 119. It will also be seen that the bolt hole 56 in the lay end is positioned to receive bolt 89, and that this same bolt holds the binder block 84 and outer end of wall 65 to the lay end when a single box is to be used and also holds the adjustable plate 104 and the block 115 to the lay end.

Having thus described my invention it will be seen that changes and modifications may be made therein by those skilled in the art without departing from the spirit and scope of the invention and I do not wish to be limited to the details herein disclosed, but what I claim is:

1. In a loom, a lay, a lay end secured thereto having a horizontal picker receiving slot, a shuttle box forming element, a shuttle binder for the element, a vertical wall forming part of the element having a picker slot extending horizontally therein in the upper part of the wall, a box floor extending horizontally forwardly from the wall below the slot, and means extending through the wall below the floor to secure the element to the lay end with the slots in the lay and the wall in horizontal alignment.

2. In a loom, a lay, a lay end secured thereto having a horizontal elongated picker guide slot terminating at the outer end in a picker receiving enlargement, a shuttle box forming element having an elongated picker guiding slot terminating at its outer end in an enlargement to receive the picker, a shuttle binder for the element, a floor forming part of the element extending horizontally and forwardly from the lay end below the slots, and detachable means to secure the element to the lay end with the guide slots and enlargements of the lay end and element in horizontal alignment.

3. In a loom, a lay, a lay end extending from the lay, a box forming element, a vertical wall forming part of the element, a box floor forming part of the element, a shuttle binder for the element, a shuttle binder supporting member, means to secure the shuttle binder supporting member to the floor of the element, and means passing through the shuttle binder supporting member, the wall of the element and into the lay end to hold the last named parts securely to the lay end.

4. In a loom, a lay, a lay end extending from the lay, a box forming element, a vertical wall forming part of the element, a box floor forming part of the element, a shuttle binder for the element, a shuttle binder supporting member, means to secure the shuttle binder supporting member to the floor of the element, holding means passing through the shuttle binder supporting member, the wall of the element and into the lay end to hold the last named parts securely to the lay end, and holding additional means passing through the wall and into the lay end to hold said element to the latter, both of said holding means being detachable to effect removal of the element from the lay end.

5. In a loom, a lay, a lay end extending therefrom, a set of shifting shuttle boxes, a guide plate for the outer end of the shifting boxes, a block separate from the lay end and the guide plate, means to prevent angular movement of the block with respect to the lay end, and means to secure the guide plate and the block to the lay end, the plate being capable of assuming different angular positions in a vertical plane with respect to the block.

6. In a loom lay, a lay end, a set of shifting shuttle boxes having a guide tongue, a guide plate having a groove to receive the tongue, a block separate from and located between the guide plate and the lay end, means to prevent angular movement of the block with respect to the lay end, and means passing through the guide plate, the block and into the lay end to hold said parts together, the plate being capable of assuming 10 different angular positions in a vertical plane with respect to the lay end.

7. In a loom, a lay capable of supporting a single box with a bolt hole therein at a given elevation with respect to the lay or a gang of 15 shuttle boxes, a guide for said boxes having a bolt hole of the same elevation with respect to the lay, a lay end extending outwardly from the lay and having a bolt hole therethrough at said given elevation with respect to the lay, and a bolt to 20 extend through the bolt hole of the lay end and through either the single shuttle box or the guide for the shuttle boxes.

8. In a loom, a lay capable of supporting a single box with a bolt hole therein at a given 25 elevation with respect to the lay or a guide for shifting boxes and having a bolt hole of the same elevation with respect to the lay, a lay end extending outwardly from the lay and having a bolt hole therethrough at said given elevation

with respect to the lay, and a bolt to extend through the bolt hole of the lay end and through either the single shuttle box or the guide for the shuttle boxes, the distance from the lay end to the front part of the single box which is engaged by the bolt being the same as the distance from the lay end measured forwardly to the front part of the guide which is engaged by the bolt. 5

9. In a loom capable of operating either with a single shuttle box or a gang of shuttle boxes, a 10 lay end having an abutting surface, two sets of box members, one set including a box back having a rear surface to engage the abutting surface and a binder support having a rear surface to engage the box back, said binder support having 15 a forward bolt engaging surface, the other set having a block to engage the abutting surface and having also a box guide in front of the block and in engagement therewith, said guide having a bolt engaging surface, the distance between the 20 engaging surface of the lay end and the bolt engaging surface of both the binder support and the guide being substantially the same, and the bolt capable of holding either the binder support or the block and box guide to the lay end, the 25 binder support being used with the single shuttle box and the block and guide being used with the shifting boxes.

BENJAMIN W. BROUWER.
